(57) **CLAIM**

The ornamental design for a tire sidewall, as shown and described.

DESCRIPTION

1. Tire sidewall
FIG. 1.1 is a Perspective view of a tire sidewall;
FIG. 1.2 is a Front view of the tire sidewall;
FIG. 1.3 is an Enlarged Front view of a portion of the tire sidewall;
FIG. 1.4 is a first Cross-sectional view of a tire sidewall portion;
FIG. 1.5 is a second Cross-sectional view of a tire sidewall portion; and
FIG. 1.6 is an Enlarged Front view of the tire sidewall portion with indications corresponding to the first and second transverse views.
The dashed lines depicting portions of the tire sidewall form no part of the claimed design. The dot-dash lines represent boundaries of the enlarged portions of the figures and form no part of the claimed design.
